Term of patent 14 years

(Cl. D80—11)

FIG. 3

FIG. 4

FIG. 5

FIG. 6

FIG. 7

FIG.8

FIG. 1 is a front perspective view of a map display cabinet embodying my new design;

FIG. 2 is a rear perspective view thereof, it being understood that the partially illustrated perforations are continuous throughout the panel where shown;

FIG. 3 is a vertical sectional view taken on line 3—3 of FIG. 1;

FIG. 4 is a cross-sectional view taken on line 4—4 of FIG. 1, the center being broken away for convenience of illustration;

FIG. 5 is a front perspective view of a modified form of the map display cabinet illustrated in FIGS. 1 through 4;

FIG. 6 is a rear perspective view of FIG. 5;

FIG. 7 is a top plan view of FIG. 5;

FIG. 8 is a vertical sectional view taken on line 8—8 of FIG. 5; and

FIG. 9 is a cross-sectional view taken on line 9—9 of FIG. 5.

This application is a continuation of my earlier filed pending applications, Serial Numbers D-77,693 and D-77,694.

The broken line representation of maps, a fluorescent lamp, shelves and their support brackets are for illustrative purposes only.

I claim:

The ornamental design for a map display cabinet, as shown and described.
